UNITED STATES PATENT OFFICE.

BERT H. HAWKINS, OF ROYAL OAK, AND EDWARD R. HANSEN, OF DETROIT, MICHIGAN, ASSIGNEES TO MCCORD RADIATOR & MFG. CO., OF DETROIT, MICHIGAN, A CORPORATION OF MAINE.

MACHINE FOR BEADING RADIATOR FINS.

Application filed December 16, 1924. Serial No. 756,181.

This invention relates to a machine for bending over or beading the outer edges of sheet-metal fin strips or plates for automobile and like radiators.

5 The main object of our invention is to provide a machine which will cut and bead or bend over the curved or rounded front edges of fin strips used in radiators having rounded or curved fronts, as employed on 10 the Studebaker cars.

A further object of our invention is to make the machine simple in its construction and automatic in its operation so that it will perform its functions as the strips to be operated upon are fed into the machine.

The invention consists further in the matters hereinafter described and claimed.

In the accompanying drawings—

Fig. 1 is a top plan view of a machine 20 constructed in accordance with our invention;

Figs. 2 and 2^a are vertical sectional views taken on lines 2—2 and 2^a—2^a, respectively, of Fig. 1;

25 Fig. 3 is a side view of the machine;

Fig. 4 is a front view of one of the hold-downs;

Fig. 4^a is an end view thereof;

30 Fig. 5 is a perspective view of one of the sheet-metal fin strips beaded by our machine;

Fig. 6 is a top plan view of the beading roller assembly, with the hold-down rollers omitted for the sake of illustration;

35 Fig. 7 is a front view of said assembly;

Fig. 8 is a vertical sectional view on line 8—8 of Fig. 7;

Fig. 9 is a vertical section on line 9—9 of Fig. 6;

40 Fig. 10 is a vertical section on line 10—10 of Fig. 1;

Fig. 10^a is a front view of a detail to be hereinafter described; and

45 Figs. 11 to 21 show the manner in which the bead is rolled on the edge of the fin plate.

The machine of our invention has a horizontal table 1 on a supporting base 2 and rotated by meshing worm and worm gear 3, 4, shown in dotted lines in Fig. 1. The worm 3 is carried by a horizontal shaft 5 under the table 1 and journaled on the base 2, as shown in Fig. 1. The shaft 5 carries driving and

loose pulleys 6, 6^a for rotating the table 1 by power.

55 The table 1 carries a plurality of hold-downs 7, 7, arranged about its outer edge and circumferentially spaced apart, as shown. Each hold-down 7 has a flat metal back 8 and an outer marginal flange 9, curved to conform to the curvature of the outer edge of the table 1 and to lie along the same when the hold-down is pressed down on the table, as shown in Figs. 1 and 2. The end portions of the flange 9 are 60 connected by a rod 10 with upright bracket arms 11, 11 secured to the table 1. Said rod 10 carries coiled springs 12, 12 at its ends with the springs hooked to the hold-down 7 and the bracket arms 11, respectively, for raising the hold-down and normally holding it in the upright inclined position shown in Fig. 4. The upper ends of the bracket arms 11 are notched as at 11^a (Fig. 70 4^a) to receive the back 8 and form stops to 75 prevent the hold-down from going back beyond the upright position shown.

75 Duplicate edge rolling assemblies A, A are arranged on opposite sides of the machine outside of the table 1, as shown in Figs. 1 and 3. These assemblies are supported by the base 2 and are alike in construction. Each assembly A has a plurality of edge-bending or forming rolls arranged in vertical pairs, as shown in Fig. 7. As illustrated, there are five pairs of rolls, all arranged closely adjacent the outer edge of the table 1 and following the curvature thereof, as shown in Fig. 1. The upper rolls are indicated by 13 to 17 inclusive, while the lower 80 rolls by 13^a to 17^a inclusive. The upper roll 15 of the middle pair or set is fixed to the inner end of a horizontal shaft 18 journaled in the supporting box 19 of the assembly, as shown in Figs. 6 to 8. Fixed to the outer end of this shaft is a sprocket wheel 20 connected by a chain 21 with a sprocket wheel on the main shaft 5 at one side of the machine and with a shaft 39 at the opposite side of the machine, as shown in Fig. 1. 100 As there illustrated, this shaft is geared to the adjacent end of the main shaft 5 so that the rolls of the two assemblies A, A will rotate in proper directions.

105 As shown in Fig. 8, shaft 18 has a gear pinion 15^b in mesh with a pinion 15^c on the

under shaft 15^a of the lower roll 15^a. The other upper rolls 13, 14, 16 and 17 have gear pinions 13^b, 14^b, 16^b and 17^b in mesh with pinions 13^c, 14^c, 16^c and 17^c on the lower shafts of the lower rolls, as shown in said Fig. 9. Between the upper pinions and in mesh therewith are idler pinions 13^e to 16^e, as shown. This entire set of pinions are driven from the shaft 18 in the same direction and at the same speed as the edge of the fin strip is passed between the rolls.

Fig. 5 shows the radiator fin plate or strip 22 after having a bead 23 formed on its rounded or curved front edge by our improved machine. This plate before being operated on by our machine is blanked out of flat stock (brass) with a straight front edge, as shown at *a* in Fig. 1. The plate 22 is also provided with the perforations or holes 24 for the water tubes (not shown), and these perforations are distributed over the entire surface of the plate in accordance with the tube arrangement, only a few of the holes being shown in Fig. 5.

The table 1 is rotated in the direction of the arrow in Fig. 1, and a plate 22 to be operated on is placed flatwise on the table 1 in front of an upstanding hold-down 7 in advance of one of the boxes 19, with the two guide pins 25, 25 in front of said hold-down extending upward through two of the holes 24, 24 in the plate to hold it in place with its front portion projecting out beyond the table, as shown. The plate is trimmed off to the curvature of the table by the rotary cutters 26, 26^a as the plate is carried by the table between said cutters. (See Figs. 1 and 10.)

In advance of these cutters is a fixed bar 27 having an intermediate portion extending diagonally over the outer margin of the table 1, as shown in Figs. 1 and 3, to be in the path of the hold-downs 7 as they are carried around by the table 1. This portion of the bar 27 is inclined upward so that the hold-downs 7 as they are moved under such portion of the bar by the table are turned down against the table by the bar to clamp the interposed plate 22 thereon. The lower end portion of the bar 27 at the cutters is straight and is spaced above the table just sufficient for the hold-downs 7 to pass under the same, as shown in Fig. 10^a. The opposite or upper end portion of the bar is also straight but is spaced above the table higher than the hold-downs 7 so that the latter while standing upright (Fig. 4^a) may pass under the upper end of the bar as they are carried by the table to contact with the intermediate inclined portion of said bar for the purpose mentioned. To this upper part of the bar is secured a shield 27^a under which the hold-downs pass on approaching the inclined part of the bar. The shield extends down in front of the table and prevents an operator from reaching in under a hold-

down as it passes under the bar 27. At the cutters is a roller 28, which bears downward on the backs 8 of the hold-downs 7 to keep them clamped against the plates while being trimmed by the cutters. This roller is carried by a spring pressed bar 28^a.

From the bar 27, the hold-down 7 passes under a roller 29 carried by the box 19. Before completely leaving this roller, the hold down 7 passes under another roller 29^a to still further hold the hold-down against the plate. By the bar 27 and rollers 28, 29 and 29^a, the plate 22 is clamped against the table 1 during the entire operation of trimming by the cutters 26, 26^a and the edge beading by the rolls heretofore described. When the hold-down 7 leaves the last roller, the springs of the hold-down raise it to release the plate, and a stripper 30 strips the finished plate from the table and it drops into a discharge chute 31, as shown in Fig. 1. The stripper 30 is forked to pass the pins 25, 25 and is inclined upward, as shown in Fig. 2^a. As there shown, the chute 31 supports the stripper.

The rolls heretofore mentioned operate on the curved front edge of the plate or sheet 22 as follows: The rolls 13, 13^a (Fig. 11) are formed to first bend up the flat edge of the sheet at the inclination shown at *b* in Fig. 14. The rolls 14, 14^a (Fig. 13) complete the turning of this flange to right-angles to the sheet, as shown at *c* in Fig. 15. The next rolls 15, 15^a curl over the upper edge of this right-angle flange, as shown at *d* in Fig. 19. The rolls 16, 16^a further turn over this flange until it meets the body of the sheet, as at *e* in Fig. 20. The rolls 17, 17^a complete the curling of the edge and make the bead as shown at *f* in Fig. 21.

With the edge forming mechanism duplicated on opposite sides of the machine, as shown in Figs. 1 and 3, the machine is capable of a double output. By rounding the outer edges of the hold-downs, the bars 27, 27 may operate on them from either end, thus enabling one set of hold-downs to be used with a plurality of stations. With the hold-downs standing at an inclination, they will readily turn down on passing under the inclined portions of the bars 27. The table and rounded edge of the plates 22 must have the same curvature. As shown in Fig. 10, the roller 29 is carried by a bar 29^b fitting loose on a bolt 29^c. Another bolt 29^d passes through the bar and carries a coiled spring 29^e, which holds the roller down against the hold-down. The roller 29^a has the same mounting.

As shown in Fig. 10, the upper cutter 26 is fixed to a shaft 32 journaled in a box on the base 2 and flexibly connected with a driving shaft 33 carrying a pulley 34 (Fig. 1). The lower cutter 26^a is on a shaft 35 having a spur gear pinion 36 in mesh with

a like pinion 37 on shaft 32. The main shaft 5 at one side of the table has a pulley 38 for a belt from the pulley 34. On the opposite side of the table, the main shaft 5 drives a shaft 39 by intermeshing gears, as shown in Fig. 1. Shaft 39 has a pulley 40 connected by belt 41 with pulley 34 of the cutters 26, 26^a at such side of the table, as shown in Fig. 1. The lower end bar 27 is fixed in the position shown by having its end bent outward and secured to the side of the bearing box for the cutters, as shown at left in Fig. 2.

The details of construction and arrangement of parts shown and described may be variously changed and modified without departing from the spirit and scope of our invention.

We claim as our invention:

1. In a machine of the character described, the combination with a circular table, of means for holding a sheet-metal radiator fin strip on the table with the curved or rounded front edge of the strip along the outer curved edge of the table, and a set of rolls along said table edge for beading the curved edge of the strip while passing between the rolls.

2. In a machine of the character described, the combination with a circular table, of means for holding a sheet-metal radiator fin strip on the table, cutter means for trimming the strip to give it a rounded or curved front edge conforming to the curvature of the curved outer edge of the table, and a set of rolls along said table edge for beading the curved edge of the strip while passing between the rolls.

3. In a machine of the character described, the combination with a table, of means for holding a sheet-metal radiator fin strip on the table with the curved or rounded front edge of the strip along the outer edge of the table, and a set of rolls along said table edge for beading the curved edge of the strip while passing between the rolls, the table edge and the setting of the rolls along the same conforming to the curvature of the curved edge of the strip.

4. In a machine of the character described, the combination with a rotary table, of a set of rolls along the table edge, and means for holding a sheet-metal radiator fin strip on the table while the rolls bead the curved or rounded front edge of the strip, said holding means acting automatically to clamp the strip on the table in advance of the rolls and releasing the strip for removal from the table after leaving the rolls.

5. In a machine of the character described, the combination with a rotary table, of a set of rolls along the table edge, means for holding a sheet-metal radiator fin strip on the table while the rolls bead the curved

or rounded front edge of the strip, said holding means acting automatically to clamp the strip on the table in advance of the rolls and releasing the strip for removal from the table after leaving said rolls, and a stripper for stripping the beaded strip from the table after being released by said means.

6. In a machine of the character described, the combination with a rotary table, of a set of rolls along the table edge, a hinged member carried by the table and having spring means to raise the same, and means including rollers and a bar above the table for swinging the member down and holding a radiator fin strip clamped on the table while the rolls bead the curved front edge of said strip, said bar being inclined upwardly and extending diagonally over the table in advance of the rolls, said member automatically rising upward to release the strip after being carried by the table from engagement with the last of the rollers.

7. In a machine of the character described, the combination with a rotary table, of two sets of rolls positioned on opposite sides of the table edge, a plurality of hinged members carried by the table and having spring means to raise the same, and means at both sets of rolls for swinging the members down and holding sheet-metal radiator fin strips clamped on the table while the rolls bead the curved front edges of the strips, said means including upwardly inclined bars, one at each set of rolls and arranged in advance thereof for acting on the members from either end.

8. In a machine of the character described, the combination with a rotary table, of a set of rolls arranged along the table edge, a hinged member carried by the table and having a back and a curved marginal flange, spring means for raising the member, and an inclined bar and rollers for swinging the member down and holding a sheet-metal radiator fin strip clamped on the table by said flange while the rolls bead the curved or rounded front edge of the strip, said bar and rollers acting on the back of said member.

9. In a machine of the character described, the combination with a rotary table, of a set of rolls along the table edge, a set of upright pins on the table to engage a sheet-metal radiator fin strip and hold it in place on the table, a member hinged to the table behind said pins, cutters for trimming the sheet to give it a curved or rounded front edge, means for swinging the member down and holding the fin strip clamped on the table while being trimmed and while the rolls bead the front edge of the strip, spring means for raising the member to release the strip after passing said rolls, and a stripper.

for stripping the strip from the pins when released by said member.

10. In a machine of the character described, the combination with a rotary table, 5 of a set of rolls along the table edge, a member hinged to the table and having spring means for raising the same, an inclined bar having an upper end and rollers for swinging the member down and holding a sheet-
10 metal radiator fin strip clamped against the table while the rolls bead the curved or rounded front edge of the strip, and means for limiting the upward swing of the member when raised to hold it in an inclined position for passing under the upper end of
15 said bar when carried into engagement therewith by the table.

11. In a machine of the character described, the combination with a circular table, 20 of means for holding a sheet-metal radiator fin strip on the table with the curved or rounded front edge of the strip along the outer curved edge of the table, and a set of rolls along said table edge for beading the

curved edge of the strip while passing between the rolls, said rolls being rotated at the rate of speed at which the edge of said strip is passed between them. 25

12. In a machine of the character described, the combination with a rotary table, 30 of a set of rolls along the table edge, a member hinged to the table and having spring means for raising the same, a bar having an upwardly inclined portion and rollers associated therewith for swinging the member 35 down and holding a sheet metal radiator fin strip clamped against the table while the rolls bead the curved or rounded front edge of the strip, and a shield secured to the upper end of said bar for the member to pass under on approaching the inclined portion of said bar. 40

In testimony that we claim the foregoing as our invention, we affix our signatures, this 28th day of October, A. D. 1924.

BERT H. HAWKINS.
EDWARD R. HANSEN.
